United States Patent Office

Des. 221,475

Patented Aug. 17, 1971

221,475

WASTE RECEPTACLE OR THE LIKE

Peter E. Norquest, 2001 Hervey, Boise, Idaho 83705

Filed Feb. 25, 1970, Ser. No. 21,613

Term of patent 14 years

Int. Cl. D7—99

U.S. Cl. D49—35

FIG. 1

FIG. 2

FIG. 1 is a top perspective view of a waste receptacle or the like showing my new design; and

FIG. 2 is a bottom perspective view with the lid exploded away and showing the sides opposite those seen in FIG. 1.

I claim:

The ornamental design for a waste receptacle or the like, substantially as shown.
